EXERCISING DEVICE FOR LUNGS AND DIAPHRAGM
Charles J. Ozment, St. Louis, Mo.
Application September 5, 1952, Serial No. 308,027
1 Claim. (Cl. 84—466)

The present device relates to an exercising device for lungs and diaphragm and it consists in the combinations, constructions and arrangements of parts herein described and claimed.

Generally there is provided an exercising device for the lungs, diaphragm and muscles relating thereto which device is particularly useful for athletes, singers and the like. The device consists essentially of a hollow cylindrical tube having a closed wall at one end thereof and an integrally formed mouthpiece at the other end thereof. Along one side of the device there is arranged a series of progressively sized openings each of which is surrounded by an integrally formed annular protuberance. The fingers of the user may be placed over these protuberances and the user then attempts to force air into the interior of the device allowing selectively one or more fingers to be removed from such protuberances so as to allow a greater or lesser escape of air from the interior of the device. The pressure thus applied to the device in varying amounts will act to exercise the muscles controlling the lungs and diaphragm of the user.

It is accordingly an object of the invention to provide a device of the character set forth which is simple in construction, inexpensive to manufacture and yet effective and efficient in use.

Another object of the invention is to provide, in a device of the character set forth, novel means for controlling the escape of air from a hollow cylinder forming a part of the invention.

A further object of the invention is to provide a device of the character set forth which lends itself to simple manufacture by molding or the like from a single piece of metal or plastic material.

Other and further objects of the invention will become apparent from a reading of the following specification taken in conjunction with the drawing, in which:

Figure 1 is a plan view of an embodiment of the invention,

Figure 2 is a side elevational view thereof,

Figure 3 is a sectional view taken along line 3—3 of Figure 1, and

2

Figure 4 is an enlarged sectional view taken along line 4—4 of Figure 3.

Referring more particularly to the drawing, there is shown therein a device of the character set forth comprising an elongated hollow cylindrical body 10 having a closed end wall 11 at one end thereof and having integrally formed at the other end thereof a mouthpiece 12. A series of openings 13, 14 and 15 is formed in one side of the body 10 and each has an annular protuberance 16, 17 and 18 respectively surrounding the same and formed integrally with the body 10.

In operation, it will be apparent that the user of the device will place the mouthpiece 12 in his mouth and then place his fingers upon the protuberances 16, 17 and 18 and thereupon will attempt to blow into the body 10 of the device. In order to exercise the muscles controlling his diaphragm and lungs, the user may then allow one or more of his fingers to move away from one or more of the protuberances 16, 17 or 18 as the case may be to thus allow the escape of a certain amount of air thus being applied by his lungs and diaphragm to the interior of the body 10. It will be noted that the openings 13, 14 and 15 are of different sizes thus making it possible to secure a relatively accurate control of the amount of air which is allowed to escape from the body 10 at any given time by allowing air to pass from one of the openings 13, 14 or 15 or from two or more of the same thus securing a great many combinations.

While but one form of the invention has been shown and described herein, it will be readily apparent to those skilled in the art that many minor modifications may be made without departing from the spirit of the invention or the scope of the appended claims.

What is claimed is:

35 An exercising device for lungs and diaphragm comprising a hollow elongated, substantially cylindrical body, a circular end wall integrally formed at one end of said body, a substantially frusto-conical enlargement integrally formed at the other end of said body and providing a mouth piece, said body having a series of differently sized openings formed in one side thereof, said openings being substantially cylindrical, and annular protuberances extending from said body, each of said protuberances surrounding one of said openings, each of said protuberances at the upper end thereof having a substantially frusto-conical enlarged bore communicating with the upper end of its respective opening.
